STEAM PLANT

Kaspar Kruse Kielland, Sogn Haveby, Aker, Norway, assignor to Ruthsaccumulator A. S., Oslo, Norway, a corporation of Norway

Application July 21, 1936, Serial No. 91,666
In Norway July 23, 1935

4 Claims. (Cl. 122—35)

My invention relates to steam plants and more particularly to a combination steam generator and accumulator.

In accordance with my invention high pressure steam generating tubes are placed within a fire tube which in turn is disposed within a low pressure container which serves as an accumulator. Excess steam generated is supplied to the accumulator where it is stored until required by an increase in load or a decrease in the rate of steam generation. The placing of the fire tube within the accumulator results in a conservation of heat inasmuch as heat transmitted through the walls of the fire tube is absorbed by the water in the accumulator and may be used to generate low pressure steam therein.

One of the advantages of my invention is that the cost for insulation, foundations and for erection of a plant are considerably less than when the generator and accumulator are two separate units. Moreover, an old fire tube boiler may be converted into a combination steam generator and accumulator by placing generator tubes in the fire tubes and using the water space of the boiler as an accumulator.

Furthermore, in accordance with my invention the steam is introduced into the accumulator through one or more nozzles located below the water level therein. This results in maintaining a circulation of water within the accumulator which is particularly important when the accumulator is heated, inasmuch as it assures an excellent heat transfer between the fire tube and the water in the accumulator.

Another object of my invention is to utilize hot water contained in the accumulator as feed water for the steam generator.

Further objects and advantages of my invention will be apparent from the following description when considered in connection with the accompanying drawing which forms part of this specification and of which:

Fig. 1 is a more or less diagrammatical cross-sectional view showing one embodiment of my invention; and

Fig. 2 is a more or less diagrammatical cross-sectional view showing another embodiment of my invention.

In the embodiment shown in Fig. 1 a fire tube 70 extends through an accumulator 71 and high pressure evaporator tubes 72 are disposed within the fire tube. Feed water is supplied to the evaporator tubes through a conduit 73 by a pump 74 which circulates water to a rectifier 18 from where it is circulated by pump 75 to the evapo-

rator tubes. A float control valve 76 is interposed between pump 74 and the rectifier and functions to maintain a substantially constant liquid level in the rectifier. Thus, upon an increase in level in the rectifier, valve 76 is closed more or less.

High pressure steam is supplied to the line 77 which conveys it to high pressure steam consumers. A conduit 78 also conveys steam through overflow valve 25 to nozzles 79 located in the water space of accumulator 71. As here shown fire tube 70 is located eccentrically with respect to the accumulator and nozzles 79 are so directed as to cause a circulation of water between the fire tube and the adjacent wall of the accumulator. Due to the fact that the space between the fire tube and the accumulator at this point is somewhat restricted, the circulation therethrough is rapid, and increases the rate of heat transfer from the tube to the water.

In order to increase the accumulator capacity, a second accumulator vessel 82 is located at substantially the same level as accumulator 71 and connected thereto at the top by means of a pressure equalizing conduit 83. A conduit 84 extends from within accumulator 71 at a point somewhat above the top of fire tube 70 and leads to the lower part of accumulator 82.

A pump 85 withdraws water from any suitable source, and circulates it through valves 86 and 87 to a conduit 88. A conduit 89 connects the lower part of accumulator 82 with conduit 88 and a check valve 90 is interposed in conduit 89. A pump 91 circulates water through conduit 92 to the upper part of accumulator 71.

Valve 86 is controlled by the pressure existing within the accumulators and is arranged to be opened by an increase in pressure therein. Valve 87 is a float controlled valve and is arranged to be closed should the liquid level within the accumulators rise to a maximum permissible height. Check valve 90 permits the flow of liquid from accumulator 82, but prevents return flow of liquid into the accumulator connected to the conduit 89.

The operation of this embodiment is as follows:

Excess steam generated is passed through overflow valve 25 to accumulator 71, where it serves to charge the accumulator. Continued introduction of steam into the accumulator increases the pressure therein, and also the temperature, and valve 86 is opened in response to the increase in pressure. This permits cold water to be supplied by pump 85 through conduit 88 and by pump 91 through conduit 92 to accumulator 71. The termination of conduit 84 within accumu-

lator 71 at a point above fire tube 70 assures that the liquid level therein will be high enough to cover the fire tube. Additional liquid flows through conduit 84 to accumulator 82. Pump 91 also withdraws liquid through conduit 89 from accumulator 82 and supplies it to accumulator 71, thereby creating a continuous circulation between these two members.

Should the requirement for high pressure steam increase so that no steam is supplied through the overflow valve 25 to the accumulators, the pressure therein tends to decrease and valve 76 is closed, thereby preventing the further introduction of cold water and arresting the decrease in pressure caused thereby. Low pressure steam may be withdrawn from the accumulators through a conduit 93 in the usual manner. This conduit may communicate with the steam space of either of the accumulators.

20 The embodiment shown in Fig. 2 is the same as that illustrated in Fig. 1, except with respect to the regulation of valves 86 and 25. As shown in Fig. 2, regulator valve 25a for controlling the admission of high pressure steam to the accumulators is controlled in accordance with the pressure existing within the accumulators, the control being such that a decrease in pressure within the accumulators opens the valve 25a to permit the introduction of additional steam. Valve 86a is regulated in accordance with the pressure in the high pressure steam line 77, the arrangement being such that an increase in pressure in the steam line opens valve 86a.

Thus, an increase in pressure in line 77, which 35 may be caused by either a decrease in demand for high pressure steam or an increase in the rate of steam generation, causes valve 86a to open, thus permitting cold water to be supplied by pumps 85 and 91 to the accumulator 71. This 40 cold water introduced into accumulator 71 tends to reduce the pressure therein, which reduction in pressure causes valve 25a to open, thus permitting the flow of high pressure steam into the accumulator to heat the cold water introduced. 45 Likewise, a reduction in the pressure in line 77 causes valve 86a to close more or less, thus reducing the amount of cold water supplied to the accumulator, whereupon the pressure therein tends to increase, which in turn results in the 50 closing of the regulating valve 25a. This reduces or prevents the flow of steam into the accumulator, thus making this steam available for use by the high pressure consumers and maintaining the pressure in the line 77 at its desired value.

55 While I have shown and described two more or less specific embodiments of my invention, it is to be understood that this has been done for purposes of illustration only as required by the patent statutes and that the scope of my invention is not to be limited thereby but is to be de-

termined by the appended claims when viewed in the light of the prior art.

What I claim is:

1. In a steam plant, in combination, a first 5 accumulator, a fire tube extending within said accumulator, an evaporator disposed within said fire tube, means for heating said evaporator to generate high pressure steam therein, a conduit connecting said evaporator with said accumulator, an overflow valve therein, a second accumulator, means for circulating water from the lower part of said second accumulator to said first accumulator, a conduit connecting the vapor spaces of said accumulators, and a conduit for conveying water from said first accumulator to 10 said second accumulator, the last mentioned conduit extending above the top of said fire tube.

2. In a steam plant, in combination, an accumulator, a fire tube extending within said accumulator, an evaporator disposed within said fire tube, means for heating said evaporator to generate high pressure steam therein, a conduit connecting said evaporator with said accumulator, an overflow valve in said conduit, a conduit for supplying water to said accumulator, a regulator 25 valve in the last mentioned conduit, and means responsive to an increase in pressure within said accumulator to open said regulator valve.

3. In a steam plant, in combination, an accumulator, a fire tube extending within said accumulator, an evaporator disposed within said fire tube, means for heating said evaporator to generate high pressure steam therein, a conduit connecting said evaporator with said accumulator, a regulator valve in said conduit, means responsive to a decrease in pressure in said accumulator to open said valve, a conduit for supplying water to said accumulator, a regulator valve in the last mentioned conduit, and means responsive to an increase in the pressure of the 40 steam generated in said evaporator to open the last mentioned valve. 35

4. In a steam generating and storing plant, in combination, a plurality of accumulators for storing low pressure steam, conduits establishing continuously open communication between the steam spaces and water spaces, respectively of said accumulators, whereby to establish equalization of pressure between said accumulators, a fire tube extending within one of said accumulators, a high pressure steam generator disposed within 45 said fire tube, means within said fire tube for heating both said generator and the contents of the accumulator within which said fire tube is disposed, means for circulating water between 50 said accumulators to thereby equalize temperature, means for conducting steam from said generator to the lower part of one of said accumulators, and means for reducing the pressure of the steam so conducted. 55
